US00D643292S

(12) **United States Design Patent**
Cordero et al.

(10) **Patent No.:** **US D643,292 S**
(b4) **Date of Patent:** **** Aug. 16, 2011**

(54) **CONTAINER RECESS**

(75) Inventors: **Jeffrey Cordero**, Rancho Santa Margarita, CA (US); **William McNeal, Jr.**, Ladera Ranch, CA (US); **Joseph Abbott**, Aliso Viejo, CA (US)

(73) Assignee: **Tri-Pack Enterprises, Inc.**, Escondido, CA (US)

(**) Term: **14 Years**

(21) Appl. No.: **29/342,784**

(22) Filed: **Sep. 1, 2009**

(51) LOC (9) Cl. **09-01**

(52) U.S. Cl. **D9/516**

(58) Field of Classification Search **D9/500, D9/516, 530, 537-540, 545, 549, 551, 553, D9/571, 574, 575, 434; 215/381-385, 379; 220/600, 604, 608, 609, 660, 669**

See application file for complete search history.

OTHER PUBLICATIONS

Seven B&W photographs taken on Sep. 9, 2010 showing a generally rectangular container with recess believed to have been first commercially introduced in Apr. 2006.

Primary Examiner — Elizabeth J Oswecki

(74) Attorney, Agent, or Firm — Advantage IP Law Firm

(57) **CLAIM**

The ornamental design for a container recess, as shown and described.

DESCRIPTION

FIG. 1 is a right upper perspective view of a container recess illustrating our new design;

FIG. 2 is a front view thereof;

FIG. 3 is a right side view thereof, the left side and right side views being identical; and,

FIG. 4 is a top view thereof.

All dashed lines are for environmental purposes only and form no part of the claimed design.
